UNITED STATES PATENT OFFICE.

CARL T. SIEBERT, OF PITTSBURG, PENNSYLVANIA.

FLY-SCREEN.

SPECIFICATION forming part of Letters Patent No. 599,641, dated February 22, 1898.

Application filed March 8, 1897. Serial No. 626,355. (No model.)

To all whom it may concern:

Be it known that I, CARL T. SIEBERT, of Pittsburgh, in the county of Allegheny and State of Pennsylvania, have invented a new 5 and useful Improvement in Fly-Screens, of which the following is a full, clear, and exact description, reference being had to the accompanying drawings, forming part of this specification, in which—

10 Figure 1 shows in front elevation a fly-screen for windows constructed in accordance with my invention. Fig. 2 is a vertical section on the line II II of Fig. 1. Fig. 3 is a detail front elevation on a larger scale, showing the 15 inside view of the screen. Fig. 4 is a similar view of the outside of the screen. Fig. 5 is a perspective view showing the construction of the piece forming the slot for passage of the flies; and Fig. 6 is a view of the sheet-metal 20 blank from which the fly-passage trough is made, the lines on which the blank is bent being indicated by dotted lines.

The object of my invention is to provide a 25 fly-screen so constructed as to exclude the entrance of flies, while permitting them to pass out from the room freely.

The device which I have invented is very 30 simple. It is cheap and easily applied and may be cut to any size for the purpose of fitting it in window-frames.

The screen proper (marked 2 in the drawings) is made of woven wire, and it is formed at intervals with transverse slots or openings 35 3, at the sides of which there are strengthening-wires 3'. The screen is also preferably provided with series of vertical strengthening-wires 4. The fly-passage troughs are inserted in the slots 3 and are made as shown in Figs. 5 and 6. Each is preferably stamped 40 in a single piece out of sheet metal, and consists of an inclined plate portion 5, having at the lower edge a marginal lip 6, with notches 7, adapted to register with the strengthening-wires 4. At the level of the upper edge of 45 the plate 5 is a strip 8, connected with the plate by webs 9, affording an intermediate slot 10. On the strips 8 are lips or fastening devices 11.

As above stated, this device may be in an 50 integral piece stamped from a single flat sheet

of metal, as shown in Fig. 6, after which the parts 8 and 9 are bent into horizontal position, the flange 6 being bent downwardly and lips 12 at the ends of the plate 5 bent back at right angles to the plane of the plate, as shown. 55 The trough may be made of wire or other material separate from the screen and insertible therein.

In applying the fly-screen to use it is cut to the size of the window-sash or door to which 60 it is to be applied. The fly-passage troughs are also cut to the desired width and are inserted in the slots 3, the flanges 6 and the lips 11 fitting against the wire fabric of the screen, so as to hold the trough in place, and the slot 65 10 and plate 5 extending to the outside of the screen. When the parts are thus arranged, flies on the inside of the screen when walking up the same will naturally follow the slot 10 at the top; but flies on the outside will not 70 pass down through the slot, for they will not pass down through a narrow slot where they have no foothold along the vertical side of the slot. The device is therefore effective in excluding flies from the room and ridding the 75 room of flies which are already there. The screen may be made, and sold, in the same manner in which ordinary fly-screens are made. It may be made in any desired width and cut to size when it is fitted to the sash. 80

The form of the device may be modified within the scope of my invention as defined in the claims, since

What I claim is—

1. A flyway comprising a hollow body which 85 is composed of two spaced plates united to each other, said body having openings in its back and top, whereby it is adapted to be secured to the face of a screen and to cover a slot therein, and means for securing said fly- 90 way to a screen.

2. A fly-passage trough comprising an upwardly and outwardly extending plate connected at the top with an inwardly-extending strip affording an intermediate slot, said strip 95 and plate having flanges or lips for securing the trough to a fly-screen.

3. A fly-passage trough comprising an upwardly and outwardly extending plate connected at the top with a strip affording an in- 100

termediate slot, said strip and plate having securing flanges or lips, all of said parts being made in a single piece of sheet metal.

4. A fly-screen having in the wire fabric a transverse slot, and a fly-passage trough set therein, said trough comprising an upwardly and outwardly extending plate connected at the top with an inwardly-extending strip affording an intermediate slot.
5. A fly-screen having in the wire fabric a transverse slot, and a fly-passage trough set therein, said trough comprising an upwardly and outwardly extending plate connected at the top with an inwardly-extending strip af-

fording an intermediate slot, said plate and strip having flanges or lips for securing the trough to the screen.

6. A fly-screen having a transverse slot in the fabric, said fabric having vertical strengthening-wires extending across said slot, and a trough having flanges or lips by which it is secured in said slot.

In testimony whereof I have hereunto set my hand.

CARL T. SIEBERT.
